UNITED STATES PATENT OFFICE

RICHARD HERZ, OF FRANKFORT-ON-THE-MAIN, AND MAX SCHUBERT AND WALTER BRUNNER, OF FRANKFORT-ON-THE-MAIN-FECHENHEIM, GERMANY, ASSIGNEES TO GENERAL ANILINE WORKS, INC., OF NEW YORK, N. Y., A CORPORATION OF DELAWARE

HYDROXY-THIONAPHTHENES CONTAINING A PYRAZOLE RING

No Drawing. Application filed December 19, 1929, Serial No. 415,351, and in Germany December 22, 1928.

Our present invention relates to new hydroxy-thionaphthenes containing a pyrazole ring, more particularly it relates to hydroxy-thionaphthene compounds which probably correspond to the general formula:

10 wherein the CH-group stands in para-position to the C-OH-group and the benzene as well as the pyrazole nucleus may contain alkyl-groups.

These compounds are produced, for instance, in the following manner:

15 A 6-amino-indazole compound corresponding probably to the formula:

20 wherein one of the positions designated by X is unoccupied and the benzene as well as the pyrazole nucleus may contain alkyl-groups, is converted into the corresponding ortho-mercaptopan, the SH-group standing in one of the positions indicated by

25 X, for instance, by treating the starting material with a sulfocyanide and a halogen and splitting up the sulfocyanic group thus introduced (compare the processes disclosed in the U. S. Patents No. 1,790,

30 097, No. 1,784,441, and No. 1,788,297). This mercaptan is condensed with mono-chloro-acetic acid to form the corresponding thioglycollic acid and this acid is transformed in the known manner into the hydroxy-thio-

35 naphthene compound. Or the sulfate of a 6-amino-indazole is transformed to the ortho-sulfonic acid by intramolecular rearrangement, the sulfonic group is converted into the corresponding acid chloride group which

40 yields on reduction the mercapto-group, and

the mercaptan is transformed into the thioglycollic acid, for instance, in the manner described in U. S. Application Serial No. 262,-038, filed March 15, 1928.

45 The pyrazole-hydroxy-thionaphthenes thus obtained are insoluble in water, easily soluble in dilute caustic alkali solutions without an addition of organic solvents.

50 In order to further illustrate our invention the following examples are given, the parts being by weight and all temperatures in centigrade degrees, but it is understood, that our invention is not limited to the particular products of reacting conditions mentioned therein.

Example 1

55 A solution of 70 parts of 6-amino-indazole (melting point 210°, described by Witt, Nöltin and Grandmougin in Berichte der deutschen chemischen Gesellschaft, vol. 23 (1890), page 3635) in 1,000 parts of methanol is mixed with 150 parts of ammonium sulfocyanide. Then a solution of 85 parts of bromine in 300 parts of methanol is allowed to run in while stirring. Ortho-sulfocyanogeno-amino-indazole precipitates in the form of colorless leaflets not yet melting at 300°, which are filtered and dried.

hours under a reflux condenser with a solution of 35 parts of caustic soda in 400 parts of water. The clear solution is mixed with a solution of 21 parts of sodium nitrite in 5 300 parts of water and the mixture is introduced at 0° into 150 parts of hydrochloric acid 20° Bé and 200 parts of ice. The clear diazo-solution is allowed to run at 30-40° into a solution of complex copper cyanide 10 corresponding to 60 parts of sodium cyanide with a simultaneous addition of 100 parts of sodium bicarbonate. When the capacity of being diazotized has disappeared the mass is acidified. The precipitated 6-cyanogeno-indazole-ortho-thioglycollic acid is filtered, 15 washed and dried.

26 parts of the raw cyanogeno-indazole-thioglycollic acid are heated to 80-90° for 8 hours with a solution of 73 parts of crystallized sodium sulfide in 31 parts of water. Then the mass is dissolved in water, filtered and acidified. The precipitated amino-pyrazole-thionaphthene-carboxylic acid is filtered off and washed. The formation of this compound takes place by an intramolecular rearrangement, probable according to one of the 25 following equations:

The moist paste of this carboxylic acid corresponding to 20 parts of the dry substance is warmed to 90-95° for 3 hours with a solution of 70 parts of concentrated sulfuric acid in 3000 parts of water. After cooling the formed hydroxy-pyrazole-thionaphthene is filtered off and dried. It represents yellow needles melting at 235°. This step of the reaction probably takes place according to one of the following equations:

Example 2

60 6-amino-2-methylindazole of the probable formula:

which is described by Auwers in Berichte der deutschen chemischen Gesellschaft, vol. 53 (1920) page 1219, is treated in the manner described in Example 1. Thereby sulfocyanogeno-6-amino-2-methyl-indazole (forming, 70 when recrystallized from alcohol, yellow leaflets melting at 280-285°) is obtained which is transformed into 6-amino-2-methyl-indazole-ortho-thioglycollic acid (melting point of the anhydride 278-280°) and this 75 latter into N-methyl-pyrazole-hydroxy-thionaphthene melting at 200°, in a manner analogous to that described in Example 1. The new hydroxy-thionaphthene compound probably corresponds to one of the following 80 formulae:

Example 3

5-methyl-6-nitro-indazole of the probable 90 formula:

which is described by Nölting in Berichte der deutschen chemischen Gesellschaft, vol. 37 (1904), page 2588, is reduced by means iron and acetic acid to form 5-methyl-6-amino indazole. This amino-compound represents 100 colorless needles melting at 240-242° and corresponds probably to the formula:

It is treated with ammonium sulfocyanide and bromide in the presence of glacial acetic acid. Thereby 5-methyl-6-amino-7-sulfocyanogeno-indazole is obtained. It forms 110 when recrystallized from butanol, colorless

prisms melting above 300° and corresponds 110 probably to the formula:

The sulfocyanogeno compounds yields when boiled with a caustic potash solution 5-methyl-6-amino-7-mercaptop-indazole of the probable formula:

5

10 The mercaptan is condensed with monochloro-acetic acid. The 5-methyl-6-amino-indazole-7-thioglycollic acid thus formed corresponds probably to the formula:

15

20 Its anhydride forms colorless prisms melting above 300°. This thioglycollic acid yields when condensed in the manner described above a hydroxy-thionaphthene compound of the probable formula:

25

25 which forms when recrystallized from monochloro-benzene, yellow leaflets melting at 285°.

We claim:

1. As new products, the hydroxy-pyrazole-thionaphthenes probably corresponding to the general formula:

40 wherein the CH-group stands in the para-position to the -C-OH-group and the 5-position of the benzene as well as the 2-position of the pyrazole nucleus may contain a methyl group, which compounds are 45 colorless to light-colored crystalline substances having a definite melting point, are insoluble in water, easily soluble in dilute caustic alkali solutions even without an addition of organic solvents, and yield when 50 oxidized grey to olive thioindigo dyestuffs. 2. As a new product, the hydroxy-pyrazole-thionaphthene probably corresponding to one of the following formulae:

55

60 which compound forms yellow needles, melting at 235° C., is insoluble in water, easily soluble in dilute caustic alkali solutions even without an addition of organic solvents, and yields when oxidized a grey thioindigo dyestuff.

3. As a new product, the hydroxy-pyrazole-thionaphthene probably corresponding to one of the following formulae:

70

75

which compound has a melting point of 200° C., is insoluble in water but easily soluble in dilute caustic alkali solutions even without an addition of organic solvents.

4. As a new product, the hydroxy-pyrazole-thionaphthene probably corresponding to the formula:

90

which compound forms yellow leaflets melting at 285° C., is insoluble in water but easily soluble in dilute caustic alkali solutions even without an addition of organic solvents.

In testimony whereof, we affix our signatures.

Certificate of Correction

September 13, 1932.

Patent No. 1,876,930.

RICHARD HERZ, ET AL.

It is hereby certified that error appears in the printed specification of the above-numbered patent requiring correction as follows: Page 2, at line 35, strike out the left-hand formula, and insert instead the formula shown below:

and that the said Letters Patent should be read with this correction therein that the same may conform to the record of the case in the Patent Office.

Signed and sealed this 16th day of May, A. D. 1933.

M. J. MOORE,

Acting Commissioner of Patents.
